COMPACT SMOKER

William M. Sewald, Jr., Crystal City, Mo.

Application April 13, 1948, Serial No. 20,802

2 Claims. (Cl. 131—242)

1

This invention relates to a compact smoker, and particularly to a folding portable type which may be carried in the pocket or in a purse.

The main object of my invention is to provide a compact folding smoker which may be opened to display a retainer plate upon which cigarettes and cigars may be laid and also an ash tray which normally is disposed under the retainer plate when the cover of the smoker is closed.

Another object is to have such a compact smoker in which the retainer plate upon which the cigarettes may be laid is provided with a large number of upwardly-directed supporting points which prevent the cigarette or cigar laid thereon from touching the retainer plate proper and provide sufficient ventilation to allow complete burning of the cigarette or cigar.

A further object is to have such a compact smoker in which the receiving plate for the cigarettes is replaceable, which is also true of the ash tray of the same device.

It is also an object to have such a compact smoker made in two parts hinged together which so completely fit together that they present a substantially air-tight container preventing the escape of ashes or dirt therefrom into the pocket-book or pocket, when carried in the latter.

It is likewise an object of the invention to have such a smoker's device which is small enough to be unobtrusive and yet contains a sufficiently large receiving plate and also ash tray as to be useful when the person using it is out in sports, at conventions, meetings, social gatherings, traveling on trains or in the air, in buses and cars, or at any place an ash tray is not otherwise furnished.

It is, of course, an ancillary object to have such a portable smoking device which is sufficiently capacious to retain cigarette stubs and ashes until a convenient time occurs for disposal of the same, while also being of such reasonable construction that it will be low in cost.

Other objects and advantages of the invention will appear more fully in detail as the specification proceeds.

In order to facilitate ready comprehension of the features of this invention, the latter is illustrated on the accompanying drawing forming part hereof, and in which:

Figure 1 is a plan view of a folding compact smoker made according to the invention and embodying the same in a practical form, the device being shown in fully open position ready for use;

Figure 2 is a side elevation of the same device in the open position;

2

Figure 3 is a section through the device on line 3—3 in Figure 1;

Figure 4 is a perspective view of the invention when the device is in closed compact condition ready to be put into a pocket or purse;

Figure 5 is a fragmentary section taken on line 55 in Figure 3;

In the various views the same reference numerals indicate the same parts.

10 It is frequently the experience of smokers that when they desire to lay aside a cigarette for a moment or perhaps dispose of the same, it is still lighted and may be a source of danger or at least a source of nuisance, and frequently requires to be freed from ashes and various other conditions arise when smoking which require attention, but all too often facilities are lacking for giving the cigarette the proper attention, or at least if the ashes shaken off or the cigarette disposed of, the danger threatened by the stub still being lit may remain and ashes about the floor or in other places may be a serious source of trouble or nuisance and inconvenience, and in some places such conditions must be prevented at all costs. Various makeshifts have been resorted to heretofore, but nothing has been generally adopted to serve the convenience of smokers in this direction, especially for smokers who are present at conventions and meetings and travel in various vehicles, or even aircraft, trains, etc., where facilities are absent for supporting lighted cigarettes and receiving the ashes therefrom and also for snubbing cigarettes and leaving the snubbed ends about, and hence there is need for something to serve such convenience on the part of a smoker using cigarettes and cigars.

However, I have found it quite feasible to provide a compact device serving the above ends in a very convenient manner, as will now be described:

40 Hence in the practice of my invention, and referring again to the drawing, the device which I term a compact smoker, generally indicated at 6, includes a casing 7 and a cover 8 hinged thereto by means of a hinge 9, while the edge 10 of the casing 7 is adapted to meet edge 11 of the cover along a common line of cleavage, and is substantially in line when the cover is open, as shown in Figures 1 to 3. Both the casing and the cover are preferably of sheet metal construction, so that this cover, for example, which is more elaborate than the casing, and therefore first to be described, includes the housing generally indicated at 12 and consisting of side walls 50 13 and bottom 14 spaced within the outer cover 55.

8 proper and its top 15. The housing 12 projects a short distance above the upper edge 11 of the cover 8 and is provided at the upper edge thereof with a bounding flange 16 bent out from said upper edge and serving to project into a corresponding recess 17 within edge 10 of the casing 7. It is thus seen that when the cover is closed, the edge 10 of the casing will close about the flange 16 in cover 8 so that the interior of the device will be quite tightly closed, and if these parts are made to interfit sufficiently close, the contents of the device will be retained without danger of any odor or dust from ashes escaping therefrom. In addition to the foregoing, it should be mentioned that the device is, of course, furnished with locking means such as the finger-pressed catch 18 having the projecting finger piece 19 extending through a slot 20 in the front wall 21 of the casing, said latch member being adapted to project into slot 22 upon the edge 11 of the front wall 23 of the cover. The cover may thus be closed and retained in closed position in a more or less conventional manner.

However, within the housing 12 in cover 8 is a retainer plate or block 24 preferably made of porous ceramic material, such as fire clay or the like, from which a large number of upwardly-extending points 25 project rigidly, being integral with said block and normally serving to support a lighted cigarette or stub so that the latter is retained out of contact with the upper face 26 of block 24, thus affording sufficient ventilation for the cigarette to continue burning until entirely consumed. These points, which may be spaced about $\frac{1}{4}$ of an inch from point to point, prevent condensation from extinguishing a cigarette burning on retainer 24. One purpose served by the fact that housing 12 is spaced within the walls and top of the cover 8 is that any heat which is transmitted by radiation from a cigarette or cigar lying supported upon points 25 will not be communicated directly to the casing, but rather distributed through the block, and in that manner more or less dissipated and lost so that it will not do any damage. Moreover, as the cigarette burning upon the points will be entirely consumed, one fire hazard is thereby eliminated, as only ashes will remain.

The casing 7 has a receiver or ash tray 28 within the same and may either be a removable tray made of any desirable material, such as glass, plastics or metal, etc., or even ceramic material, but in the present case it is shown as being of sheet metal and formed with a shoulder or flange 27 communicating directly with the recessed portion 17 by joining the lower edge thereof and thereby forming part of the casing. The casing and the cover thus far described virtually form double-walled members, but it is, of course, possible to make them solid so that other materials, such as incombustible plastic or ceramics or the like may be used instead of metal.

Returning again to the infusible block 24, it is to be noted that the same is a separate replaceable unit, so that it will easily be possible to remove a block which may have become too saturated with smoke odors, nicotine and the like, and replace it with a new one costing but a few cents. However, while in the container it is intended that the block will be firmly held in place so that it will not accidentally be displaced therefrom. This end is accomplished by means of a pair of manually-depressible spring catches

29 associated with the cover and having shoulder portions 30 adapted to engage the beveled edge 31 of block 24. The spring catches extend a sufficient distance downwardly to a point indicated at 32 in the side walls 33 of the housing 12 and are preferably integral therewith, so that said catches will be sufficiently resilient to allow the finger to press upon the upper end thereof and thereby cause them to recede a sufficient distance into their slots 34 to clear the block and allow it to be removed from the inner container.

While the casing and the cover forming the present device are shown substantially square with exteriorly rounded edges, yet this device could have some other geometrical form if desired, and especially would this be true of the ceramic block 24 which could be round, oval or have any other outline according to the whim of the maker. It would also be feasible to insert the casing 7 with its ash receiver in appropriate positions on furniture and in various useful locations, where the cover 8 with its ceramic block 24 will readily serve to close the device as already described. The supporting points 25 on the block are shown arranged in vertical and transverse straight lines, but the arrangement could be entirely different if desired, that is, they could be arranged in circles or in other patterns as desired, this forming no particular feature of the invention.

Manifestly, variations may be resorted to and parts and features may be modified or used without others within the scope of my invention, and as particularly pointed out in the appended claims.

Having now fully described my invention, I claim:

1. In a portable compact, the combination with 40 a receptacle having one end open and including a bottom and side walls and a cover hingedly connected to said receptacle for movement toward and away from the open end of the latter, of a cigarette rest mounted within said cover, said rest comprising a housing arranged in spaced relation with respect to said bottom and side walls of said receptacle and fixedly secured to said side walls, a retaining block positioned within said housing and having one face thereof resting upon a portion of said housing, means on the inner face of said housing engaging said retaining block for holding the latter within said housing, and a plurality of vertically disposed cone-shaped members positioned in spaced relation 50 with respect to each and fixedly secured to the other face of said retaining block, whereby a lighted cigarette may be supported out of contact with the other face of said block.

2. In a portable compact, the combination with 60 a receptacle having one end open and including side walls and a cover hingedly connected to said receptacle for movement toward and away from the open end of the latter, of a cigarette rest mounted within said cover, said rest comprising a housing arranged in spaced relation with respect to said bottom and side walls of said receptacle, and fixedly secured to said side walls, a retaining block positioned within said housing and having one face thereof resting upon a portion of said housing, said block having the edges of said one face beveled, means carried by said housing for engaging the beveled edges of said block for holding the latter within said housing, said last named means comprising spring catches having finger portions for engaging said beveled edges

of said block, and a plurality of vertically disposed cone-shaped members positioned in spaced relation with respect to each other and fixedly secured to the other face of said block, whereby a lighted cigarette may be supported out of contact with the other face of said block.
